UNITED STATES PATENT OFFICE.

WILLIAM A. PENFIELD, OF MERIDEN, CONNECTICUT, ASSIGNOR TO BRADLEY & HUBBARD MFG. CO., OF MERIDEN, CONNECTICUT, A CORPORATION.

WICK-STOP FOR LAMP OR OIL-HEATER BURNERS.

SPECIFICATION forming part of Letters Patent No. 691,710, dated January 21, 1902.

Application filed May 4, 1901. Serial No. 58,762. (No model.)

To all whom it may concern:

Be it known that I, WILLIAM A. PENFIELD, of Meriden, in the county of New Haven and State of Connecticut, have invented a new Improvement in Wick-Stops for Lamp or Oil-Heater Burners; and I do hereby declare the following, when taken in connection with the accompanying drawings and the numerals of reference marked thereon, to be a full, clear, and exact description of the same, and which said drawings constitute part of this specification, and represent, in—

Figure 1, a broken view in vertical section illustrating one form of my invention applied to the burner of an oil-heater; Fig. 2, a broken view showing one mode of securing my improved wick-stop collar to the outer wick-tube of the burner; Fig. 3, a detached plan view of the collar; Fig. 4, a broken view, in vertical section, showing the threading of the wick-stop collar and the outer wick-tube for the removable attachment of the former to the latter.

My invention relates to an improvement in lamp or oil-heater burners, the object being to provide simple, convenient, and reliable means for preventing smoking by positively limiting the upward movement of the wick beyond a predetermined and safe height.

With these ends in view my invention consists in a lamp or oil-heater burner having its outer wick-tube provided with a wick-stop collar extending into the path of the wick to limit the upward movement thereof and exposing the wick sufficiently to leave it free to burn.

My invention further consists in certain details of construction and combinations of parts, as will be hereinafter described, and pointed out in the claims.

In carrying out my invention as herein shown I employ an independently-formed wick-stop collar 2, adapted in internal diameter to fit snugly over the outer wick-tube 3, of which it forms an upward extension and the upper end of which is located in the same horizontal plane as the upper end of the inner wick-tube 3^a. The upper edge of this collar is turned inwardly and downwardly to form a flange 4, the edge of which is cut or

notched to form a continuous series of downwardly-pitched wick-stop teeth 5, which extend into the path of the wick, so as to limit the upward movement thereof, but which expose enough of the entire area of its upper edge to permit the same to burn freely. The size, separation from each other, and number of these teeth may be varied as desired.

In order to provide for convenient access to the wick for trimming the same or for rubbing its charred edge away, the wick-stop collar is constructed for removable attachment to the outer wick-tube. For that purpose a variety of constructions may be resorted to. As shown in Figs. 1 to 3, inclusive, of the drawings, the lower edge of the collar is formed with three inclined bayonet-slots 6, located equidistant from each other and coacting with three correspondingly-arranged locking-pins 7, mounted in the outer wick-tube 3. For additional strength the edge of the collar is not cut through in making the slots, but struck outwardly to form bridge-like loops 8, which straddle, as it were, the lower ends of the short legs of the slots. In applying the collar to the outer wick-tube the short legs of the slots 6 are registered with the pins 7, after which the collar is turned so as to cause the inclined lower walls of the long legs of the slots to ride under the pins, whereby the collar is drawn down into place. When the collar is thus locked to the outer wick-tube, it cannot be lifted by the wick, the upward movement of which will therefore invariably be stopped at a predetermined point at which the lamp will not smoke. When the wick is lifted, it will impinge upon and be stopped by the teeth 5 of the collar, as they are located directly in the path of its upward movement; but, as aforesaid, they expose so much of it that they will not prevent it from burning freely. I do not, however, limit myself to removably attaching the wick-stop collar to the outer wick-tube by the use of the bayonet-slots and locking-pins described, as a variety of other means may, as above described, be resorted to for the same purpose. Thus I may, as shown in Fig. 4, form the lower end of the wick-stop collar 2 with internal threads and the upper end of the outer

wick-tube 3 with external threads, whereby the collar may be readily removed and replaced.

As herein shown, the burner is provided 5 with a spreader 9, which may be of any approved construction, and with a cone 10, resting upon the burner-skirt 11, which is set in the usual manner into the fount 12, which is provided with wick-adjusting apparatus 13 10 of any approved character.

Although the burner shown is primarily designed to be used for an oil-heater, my improved wick-stop collar may be applied with equal advantage to burners designed for illuminating-lamps and in any size. 15

In view of the modifications shown and described, as well as those suggested, and of others which may obviously be made, I would have it understood that I do not limit myself 20 to the precise construction herein shown, but hold myself at liberty to make such changes and alterations as fairly fall within the spirit and scope of my invention.

Having fully described my invention, what I claim as new, and desire to secure by Letters 25 Patent, is—

In a lamp or oil-heater burner, the combination with the inner and outer wick-tubes thereof, the same having their upper ends located in the same horizontal plane, of an 30 independently-formed removable wick-stop collar adapted to be set over the upper end of the said outer wick-tube and provided with an inwardly-turned flange, the edge of which is cut to form a series of teeth which 35 limit the upward movement of the wick and expose the same sufficiently to permit it to burn between them.

In testimony whereof I have signed this specification in the presence of two subscr- 40 ing witnesses.

WILLIAM A. PENFIELD.
